UNITED STATES PATENT OFFICE.

SAMUEL J. HART, OF SYRACUSE, NEW YORK, ASSIGNOR TO JOHN R. CLANCY, OF SYRACUSE, NEW YORK.

HOSE-CLAMP VISE.

1,177,032.

Specification of Letters Patent. Patented Mar. 28, 1916.

Application filed June 15, 1915. Serial No. 34,152.

To all whom it may concern:

Be it known that I, SAMUEL J. HART, a citizen of the United States, residing at Syracuse, in the county of Onondaga and State of New York, have invented new and useful Improvements in Hose-Clamp Vises, of which the following is a specification.

This invention relates to vises and consists in improvements therein designed particularly for adapting the vises of my invention to be used in the operation of tightening the standard types of one piece sheet metal hose clamps. As is well known, the band of a clamp of the type referred to is slotted at each side; by the forming of an integral tongue at one side and at the opposite side to provide an opening for the end of the tongue.

An important feature of my invention resides in an improved form of vise jaw which is adapted to engage the ordinary clamp which has no special provision therefor, as the shoulders aforesaid. To that end I have devised a vise jaw of peculiar form to effect engagement with the clamp within the slots thereof, for this purpose having a shoulder formed thereon to fit into the slot of the clamp and engage the wall thereof. My improved arrangement is thus suited to engage the clamps of standard form and furthermore the means of engaging the clamps so provided performs an additional important function of rigidly holding the clamp in proper alinement with the jaws against any tendency to twist when subjected to the tightening pressure.

The described and other features of my improved vise are shown in the accompanying drawing wherein the reference characters of this description are applied to like parts in the several views.

In the drawing Figure 1 is a view in side elevation of a vise embodying the features of my invention and illustrating the hose clamp in position to be tightened thereby, the hose clamp being shown in section. Fig. 2 is a horizontal sectional view on line 2-2 of Fig. 1 as viewed from the under side. Fig. 3 illustrates the vise in vertical cross section on line 3-3 of Fig. 1 and Figs. 4 and 5 are respectively an end elevation and bottom plan view of one of the jaw members detached.

The construction here shown embodies the bearing and supporting frame 1 of angular form having the base portion 2 and the oppositely arranged arms or uprights 3-3'. These arms support the stationary and movable jaw members 4 and 5 respectively, the former being secured to the arm by having a reduced shank 6 thereon fitted to an aperture in the arm. The movable jaw 5 is carried by a reciprocating slide 8 of angular form and fitted to a suitable bearing aperture in its supporting arm 3' so as to support the movable jaw in alinement with the opposite jaw 4. The movement of the slide 8 is controlled by the feed screw 9 journaled in the vertical arm of the slide and threaded to the supporting arm 3' whereby upon being rotated by means of lever pin 10, fitted to the end thereof, it will be moved to advance and retract the jaw 5 with reference to the co-acting jaw 4.

For supporting the hose clamp in position to be engaged by the jaws I have provided an adjustable shelf or rest member 12 pivotally supported on pins 13 by the slotted supporting arms 14-14 secured to the frame 1 by the clamping bolts 15 having nuts 16. The arrangement as described permits of adjusting the rest 12 to accommodate clamps of different sizes.

The clamp, as shown, is one of a standard form of one piece sheet metal clamps and is struck up from sheet metal to form the circular straps or band 18 having its ends outwardly bent into the ears 19-19 which are perforated to receive the tightening and securing screw 20 having the securing nut 21 on its end as shown. The band of the clamp is provided with the elongated slots 22-23 at each side which assist in gripping the hose and have the additional important function of permitting the metal, in forming the slot 22, to be bent inwardly to form the tongue 24 to span the space between the ends of the clamp so that the clamp when applied to the hose will engage it throughout its full circumference. The tip of the tongue 24, as shown, is received in the opposite slot 23 to the end that it shall not bite into the hose.

As aforesaid, an important feature of my improved vise consists in adapting it for tightening hose clamps of the general type

described wherein no special raised portions or shoulders are provided for engagement therewith. For this purpose I have formed the jaws, as shown, with small shoulders 25 arranged to enter the slots 22-23 of the clamps and engage with the metal forming the upper wall of the slots. A desirable manner of forming these shoulders is here shown wherein the jaws are made from flat 5 bars of square form having their under sides beveled off at the end to each side of the center portion so as to form central shoulder 25 which is of a size to enter within the slots of the clamp as described. In so forming 10 the shoulders, it will be seen that the beveled side portions 26-26 will engage the peripheral surface of the clamps to bear thereon during tightening and maintain the proper engagement of the shoulder 25 with 15 the clamp. The engagement of the jaw and the clamp as provided for by the shoulders entering the slots, in accordance with my invention, possesses the additional advantage of securely holding the clamp from twisting 20 sidewise when under pressure during tightening. The form of jaw shown will also permit of tightening the special forms of clamp wherein special lugs or shoulders are provided.

25 30 The manner of using my improved vise will be obvious from the foregoing description and it will be understood that upon tightening the clamp by means of the vise the clamping screw thereof is then screwed 35 up to clamp it in position before the clamp is released by the retraction of the jaw 5. To give access to the screw 20 for tightening it with a screw driver I have formed the supporting arms 3-3' with recesses 28 on their 40 upper surfaces as shown.

As many changes could be made in the above described construction without departing from the scope of my invention it is intended that all matter contained herein 45 shall be interpreted as illustrative and not in a limiting sense.

Having described my invention, I claim,

50 1. A vise for tightening hose clamps comprising a supporting frame having oppositely arranged supporting arms, a stationary jaw carried by one arm, a movable jaw slidably supported in the opposite arm, a feed screw arranged to control the movement of the movable jaw and an adjustably supported shelf arranged to support the clamps relative to the jaws, said shelf being elongated to provide support for clamps of different sizes, substantially as described.

55 60 65 2. A vise for tightening hose clamps having side slots therein comprising co-acting jaw members suitably supported for engaging the clamp and means to effect relative movement of the jaws for tightening the clamp, said jaws being formed with shoulders of a size to enter the slots in the clamp and with por-

clamp and with portions adjacent to the shoulder to engage the surface of the clamp substantially as described.

3. A vise for tightening hose clamps, comprising a supporting frame having oppositely arranged supporting arms, a stationary jaw carried by one arm, a movable jaw slidably supported in the opposite arm, a feed screw arranged to control the movement of the movable jaw, and an adjustably supported shelf to support the clamps relative to the jaws and said supporting arms being recessed to give access to the clamp-screw for tightening the same, substantially as described. 70 75 80

4. A vise for tightening hose-clamps, comprising a supporting frame having oppositely arranged supporting arms, a stationary jaw carried by one arm, a slide fitted to a bearing in the opposite arm, a co-acting jaw on the slide, a feed screw arranged to control the movement of the slide, a supporting shelf, slotted arms pivoted thereto and clamping bolts fitted to the slots of the arms for adjustably securing the shelf in position 85 relative to the jaws the supporting arms being recessed on their upper surfaces to give access to the clamp screw for tightening the same, substantially as described. 90 95

5. A vise for tightening hose clamps comprising a supporting frame having oppositely arranged supporting arms, a stationary jaw carried by one arm, a movable jaw on the opposite arm, means to effect movement of the movable jaw with relation to the stationary jaw and an adjustably supported shelf arranged to support the clamp relative to the jaws, said shelf being elongated to provide support for clamps of different sizes, substantially as described. 100 105 110 115

6. A vise for tightening hose clamps having side slots therein, comprising a supporting frame having oppositely arranged supporting arms, a stationary jaw carried by one arm, a movable jaw slidably supported in the opposite arm, a feed screw arranged to control the movement of the movable jaw, an adjustable shelf arranged to support the clamps relative to the jaws and said jaws being formed with shoulders of a size to enter the slots in the clamp and with portions adjacent to the shoulder to engage the surface of the clamp substantially as described. 120 125 130

7. A vise for tightening hose clamps having side slots therein, comprising a supporting frame having oppositely arranged supporting arms, a stationary jaw carried by one arm, a movable jaw slidably supported in the opposite arm, means to effect the movement of the movable jaw relative to the stationary jaw, an elongated shelf adjustably supported relatively to the jaws, said jaws being formed with shoulders of a size to enter the slots in the clamp and with por-

tions adjacent to the shoulder to engage the surface of the clamp and said supporting arms being recessed to give access to the clamp screw for tightening the same substantially as described.

8. A vise for tightening hose clamps comprising a supporting frame, having a flat base portion, to stand on a bench and upwardly extending integral arms oppositely arranged, an adjustable shelf supported on the base between the arms and oppositely arranged jaws supported by the arms to engage with the clamps, one of said jaws being movable substantially as described.

15 9. A vise for tightening hose clamps comprising a supporting frame for the parts and the clamp, said frame having a flat base por-

tion, to stand on a bench, and upwardly extending parallel side arms, oppositely arranged parallel jaws supported in the arms 20 to engage with the clamp, one of said jaws being fixed and the other being movable toward and from said fixed jaw and an adjustable shelf for the clamp support on the base between the arms, substantially as 25 described.

In testimony whereof I have signed my name to this specification in the presence of two subscribing witnesses.

SAMUEL J. HART.
